UNITED STATES PATENT OFFICE.

HARRY W. MARSH, OF FINDLAY, OHIO.

PULLEY.

SPECIFICATION forming part of Letters Patent No. 771,879, dated October 11, 1904.

Application filed August 12, 1903. Serial No. 169,211. (No model.)

To all whom it may concern:

Be it known that I, HARRY W. MARSH, a citizen of the United States, residing at Findlay, in the county of Hancock and State of Ohio, have 5 invented new and useful Improvements in Pulleys, of which the following is a specification.

My invention relates to improvements in pulleys or sheaves, more particularly that class over which are passed ropes or cables; 10 and it has for its object, among other things, to reduce the weight thereof to the minimum, to increase the wearing capacity of the same, and whereby the wearing-surface of such may in a measure be renewed as circumstances suggest.

The nature of said invention consists of the combination of parts, including their construction and arrangement, substantially as hereinafter more fully described, and specifically 20 pointed out by the claim.

In the accompanying drawings, illustrating the preferred embodiment of my invention, Figure 1 is a section thereof with the removable plate and rim or core omitted, taken on 25 the line *a a* of Fig. 2, disclosing more especially the alternating lugs or projections upon the lateral circular members. Fig. 2 is a transverse section taken on the line *x x* of Fig. 1. Fig. 3 is a similar section taken on the line *z z* 30 of Fig. 1, showing more particularly one of the lugs or projections aforesaid.

In carrying out my invention I produce the pulley 1, preferably of a principal disk-like member or part 1^x, the shaft 2, carrying the 35 same, being preferably cast or in one piece therewith. Said member or part has an integral enlargement or shoulder 1^a at its outer circular edge upon which is slipped or fitted a leather or rubber rim or core 3, forming a 40 bearing or wearing surface for a rope or cable (not shown) passing in contact therewith, which, it is obvious, can be readily renewed when unduly worn by substituting a like part therefor, and thus increase durability. An 45 annulus or ring 4 is arranged or adapted to be fitted upon the shoulder or enlargement 1^a of the part 1^x, which parallels a corresponding offset portion 4^a of said shoulder and combines therewith to clamp or secure said leather 50 or rubber core laterally in place, said annulus

or ring 4 being held thereto preferably by suitable bolts passed through holes formed in said annulus and said offset portion 4^a. Said annulus and offset portion are formed upon their facing surfaces with lugs or projections 55 6, alternating each other and which are designed to pass through said core or rim to prevent the radial displacement of said core or rim by the impingement or friction of the cable or rope coming in contact therewith. 60 Also in lieu of passing the lugs or projections 6 through said core the bolts above noted, connecting the annulus or ring to said offset portion of the principal part or member of the pulley, may be passed through said core or 65 ring.

The additional advantage of lightness as well as cheapness of construction is apparent from the aforesaid combination and arrangement of parts.

It will be understood that latitude is allowed herein as to details, as they may be changed at pleasure without departing from the spirit of my invention and said invention still be protected.

Having thus described my invention, what I claim as new, and desire to secure by Letters Patent, is—

A pulley comprising a body portion having an integral offset peripheral extension, itself 80 having integral lateral lugs or projections, an annulus having also external lateral lugs or projections and fitting upon the periphery of said body portion, and a fibrous rim or core encompassing said periphery, intermediately of 85 said peripheral extension and annulus, the lugs or projections of said latter parts alternating each other and extending in opposite directions through said rim, with their free ends abutting or engaging said annulus and extension, respectively, thus securing said rim, 90 throughout its entire cross-sectional area and at close intervals to said annulus and extension.

In testimony whereof I have hereunto set my hand in presence of two subscribing witnesses.

HARRY W. MARSH.
